G. E. THACKRAY,
DRAFT RIGGING.
APPLICATION FILED FEB. 1, 1921.

1,394,374.

Patented Oct. 18, 1921.

Inventor
Geo. E. Thackray

UNITED STATES PATENT OFFICE.

GEORGE E. THACKRAY, OF WESTMONT BOROUGH, PENNSYLVANIA.

DRAFT-RIGGING.

1,394,374.

Specification of Letters Patent.

Patented Oct. 18, 1921.

Original application filed March 10, 1920, Serial No. 364,618. Divided and this application filed February 1, 1921. Serial No. 441,673.

To all whom it may concern:

Be it known that I, GEORGE E. THACKRAY, a citizen of the United States, and a resident of the borough of Westmont, county of Cambria, and State of Pennsylvania, have invented certain new and useful Improvements in Draft-Rigging; and I do hereby declare the following to be a full, clear, and exact description of the invention, such as 10 will enable others skilled in the art to which it appertains to make and use the same.

My invention relates to improvements in draft rigging for mine or other cars with the object of simplifying and strengthening the 15 construction thereof, and this application constitutes a division of my application for Letters Patent on improvements in draft rigging, filed March 10, 1920, Serial No. 364,618.

20 In certain prior draft rigging devices the draw bar yoke has at the rear end a reduced section and it is therefore liable to breakage from the constant effect of buffing or pulling. This breakage not only ties up equipment and causes delay, but is a frequent 25 source of damage and causes runaway cars, collisions, derailments, etc., with consequent injury or destruction to men and materials. It is also more expensive to produce a yoke 30 of the type mentioned with reduced rear portions, and economy and greater strength may be obtained by using a draw-bar yoke of constant section, thereby reducing the tendency to break and eliminating the evil 35 effects resultant therefrom.

I also provide an inner member of constant section, secured or riveted to the outer draw-bar yoke, and thereby produce a more rigid design and one better adapted to withstand 40 the shocks and wear to which the parts are subjected from the constant buffing and pulling effects when in use.

My invention is particularly adapted to mine or other cars made of metal and is so 45 fashioned that a part of the car floor serves as a center sill, the latter providing a suitable receptacle for the draft rigging.

Having thus given a general description 50 of my invention, I will now, in order to make the matter more clear, refer to the annexed sheet of drawings, which forms part of this specification, and in which like characters refer to like parts.

Figure 1 is a vertical longitudinal section 55 elevation taken on the line I—I of

Fig. 2, showing my improved draft rigging and enough of the car to illustrate the application of my invention; Fig. 2 is a top plan view of the draft rigging and a portion of the car body to which it is secured; Fig. 3 60 is a vertical longitudinal sectional elevation similar to Fig. 1, showing a slightly modified form of my improved draft rigging; Fig. 4 is a vertical transverse section taken on the line IV—IV of Fig. 3; Fig. 5 is a face view 65 of one of the follower plates; and Fig. 6 is a vertical transverse section taken on the line VI—VI of Fig. 2.

Referring now to the characters of reference on the drawings:—1 is a part of the 70 car body having the trough-shaped central portion 2, over which is fastened at each end of the car the trough-shaped reinforcing plate 3. The end sheet 4 of the car has mounted on it the bumper plate 5. The 75 cheek plate 6 over the draw-bar and the draft gear supporting plate 8 have in them the holes 7 and 9 respectively in which the reduced ends of the front follower block 10 and the rear follower block 11 fit and slide. 80 The outer draw-bar yoke 12 and the inner member 13 are of substantially constant section throughout. The buffer 14 is a special shaped metal piece, the draw-head being an integral part thereof and is riveted to both the draw-bar yoke 12 and the member 13. 85 Fig. 15 shows a type of corrugated spring plates adapted for use with this draft rigging, or if preferred, helical springs 19 may be used as shown in Fig. 3. Figs. 3 and 4 illustrate 90 a modification in which the design is strengthened by the addition of the supporting plate 16, which has riveted thereto the bottom cheek plate 17 provided with holes 18 in which the ends of the follower 95 blocks 10 and 11 fit and slide.

The cheek plates themselves are provided with the slots 7 and 18 therein, and the end portions of the same are securely riveted by a number of rivets to the car or supporting member and the central portion between the slots is also riveted so as to provide very substantial stops for the follower plates and have a large number of rivets which are of greater strength than any buffing or pulling 105 stresses to which the stops will be subjected, so that the construction is very substantial. The cheek plates are also of considerable thickness to provide ample bearing and contact surfaces. The draft gear support plate 110

as shown in Fig. 1 serves as a bottom cheek plate but as illustrated in Fig. 3 this is supplemented by another stop plate 17, the construction and securing of which is similar to 5 that of the upper stop plate 6.

It will readily be seen that my invention provides a firmly mounted draft rigging and since the draw-bar members are of constant section throughout, the full working 10 strength of the metal is available in every part of the draw-bar and particularly so at the inner end where the shocks are absorbed through the springs and thence conveyed to the car.

15 Although I have described and illustrated my invention in considerable detail, I do not wish to be limited to the exact and specific details thereof as shown and described, but may use such modifications in, 20 substitutions for, or equivalents thereof, as are embraced within the scope of my invention, or as pointed out in the claims.

Having thus described my invention, what I claim and desire to secure by Letters Patent is:—

1. In a draft rigging, an upper cheek plate secured to and within a longitudinal central trough-shaped portion of the car body, a trough-shaped supporting plate removably attached to the car body which, with the central trough, forms a draft rigging space, a lower cheek plate secured to and within said supporting plate, each cheek plate being provided with a pair of 30 substantially rectangular slots, a yoke of U-form, substantially constant in cross section mounted between said plates and adapted to be guided and supported thereby, a closure between the forward portions of said 35 yoke, a pair of follower plates mounted within and between the end of said yoke and said closure, said follower plates each having an extension narrower than the body portion of the same projecting within the slots 40 45 aforesaid, and a spring mounted between the said follower plates.

2. In a draft rigging, a U-shaped yoke with a closure between the longitudinal portions thereof, thereby providing an approximately rectangular opening therein, a pair 50 of follower plates mounted within said yoke, with one near each end of said opening, said follower plates each having upper and lower integral extensions of narrower width than the body portion thereof, an upper cheek plate secured to and within a central longitudinal trough-shaped portion of the car body, a trough-shaped supporting plate removably attached to the car body, which, 55 with the central trough, forms a draft rigging space, a lower cheek plate secured to and within said supporting plate, adapted to support and guide said yoke, each cheek plate being provided with a pair of slots of

slightly greater width than the extensions 65 of the follower plates and into which said extensions project, and a spring mounted between said follower plates.

3. In a draft rigging, a draw-bar yoke of substantially constant section provided with 70 a closure between the extending legs thereof forming an approximately rectangular opening, a follower plate mounted within and near each end of said opening, each follower plate having an extension of less width projecting from the opposite ends thereof, an upper cheek plate secured to and within a longitudinal central trough-shaped portion of the car body, a trough-shaped supporting plate removably attached to the car body, 80 which, with the central trough, forms a draft rigging space, a lower cheek plate secured to and within said supporting plate, each cheek plate being provided with a pair of slots into which said extensions project, and 85 a spring between said follower plates.

4. In a draft rigging, a yoke of approximately U-shape and substantially constant section having a closure between the extending portions thereof adapted to form a 90 substantially rectangular opening, an upper cheek plate secured to and within a longitudinal central trough-shaped portion of the car body, a trough-shaped supporting plate removably attached to the car body, which, 95 with the central trough, forms a draft rigging space, the boundaries of which are adapted to contact with, support and guide the draw-bar yoke, a lower cheek plate secured to and within said supporting plate, 100 each of said cheek plates being provided with a pair of rectangular slots therein, follower plates mounted within and near the ends of the rectangular opening of said yoke, each provided with a pair of opposite integral portions of less width extending outwardly from said yoke and fitting within the slots of the cheek plates aforesaid.

5. In a draft rigging, a draw-bar chamber formed by an upwardly extending trough 110 in the car bottom and a trough-shaped supporting plate secured below the same, top and bottom cheek plates mounted and secured therein, each provided with a pair of substantially rectangular slots, a yoke of U-shape provided with a closure, slidably mounted between said cheek plates and adapted to be supported and guided thereby, a forward and after follower plate with reduced end portions mounted within and adjacent the closure and the end of said yoke, respectively, the reduced ends of which follower plates project beyond said yoke and into the slots of the cheek plates aforesaid, and a spring between said follower plates.

In witness whereof I hereunto affix my signature.

GEORGE E. THACKRAY.
